G. T. FIELDING

DISPLAY DEVICE

Filed March 11, 1922

Inventor:
George T. Fielding
by *Albert Davis*
His Attorney

UNITED STATES PATENT OFFICE.

GEORGE T. FIELDING, OF STAMFORD, CONNECTICUT, ASSIGNEE TO GENERAL ELECTRIC COMPANY, A CORPORATION OF NEW YORK.

DISPLAY DEVICE.

Application filed March 11, 1922. Serial No. 543,064.

To all whom it may concern:

Be it known that I, GEORGE T. FIELDING, a citizen of the United States, residing at Stamford, in the county of Fairfield, State 5 of Connecticut, have invented certain new and useful Improvements in Display Devices, of which the following is a specification.

The present invention relates to display 10 devices for use for advertising and selling purposes and has for its object to provide an improved structure and arrangement in a device of this character.

For a consideration of what I believe to 15 be novel and my invention, attention is directed to the accompanying description and the claims appended thereto.

One application of my invention is in connection with house wiring devices and 20 particularly outlet boxes wherein one or more box bodies of different dimensions are provided each body being adapted to have any one of a plurality of covers fitted thereon, different covers being adapted for different 25 wiring members, and I have particularly illustrated my invention in this connection. It will be understood, however, that the invention is not necessarily limited to this particular use but may be used 30 wherever found applicable.

In the drawing the figure is a front elevation of a structure embodying my invention.

Referring to the drawing, 5 indicates a 35 post having a base 6 upon which the device stands. If desired base 6 may be screwed to a support, holes 7 being provided in it for this purpose. At the upper end of post 5 is a plate 8 which may carry suitable advertising matter and a lamp 9 for illuminating 40 purposes. Mounted on the top of post 5 are three outlet box bodies 10, 11 and 12. These may represent all the box bodies required for a certain type of house wiring. 45 They are rigidly mounted in position, body 10 being mounted directly on top post 5 and bodies 11 and 12 being carried on the ends of pipes 13 fastened in knockout openings in box body 10.

50 Each box body is adapted to have used with it a number of different covers each of which is adapted for a different wiring condition. For example one cover may form with the box body a box adapted to receive 55 a snap switch, another cover may form with

it a box adapted to receive a plug receptacle and so on, there being a sufficient number of different covers for each body, to meet the requirements ordinarily met with in wiring. As is well understood, the various devices to be put in the box are in general fastened to the cover which is in turn fastened to the box body. According to my invention I support adjacent to each box body, a string 60 comprising one each of the various covers adapted to be used with such body. The string of covers is supported one below another on a suitable chain so each is displayed and any one may be fitted to the body with which it is intended to be used. In the 65 drawing, the strings of covers are designated 15 and each cover is supported by a short chain 16 attached at a suitable point along a longer chain 17. This readily permits any cover of a string to be fitted to its 70 box body so that a prospective customer may by means of the device pick out a box body and cover to meet his needs.

The device makes an attractive display 75 rack and one of great utility in selling the apparatus for it enables a customer to at once see the complete line of apparatus available and ascertain his needs without the salesman being required to get out separately a large number of pieces to show to the customer. At night the lamp 9 may be burned 80 to display the device, the cord connection for it being indicated at 18.

In accordance with the provisions of the 85 patent statutes I have described the principle of operation of my invention, together with the apparatus which I now consider to represent the best embodiment thereof, but I desire to have it understood that the apparatus shown is only illustrative and that the 90 invention may be carried out by other means.

What I claim as new and desire to secure by Letters Patent of the United States, is:

1. In a display device for apparatus comprising a major element and a number of minor elements each of which is adapted for use with the major element, the combination of a standard, a major element fixed thereon, and a string of minor elements hung adjacent thereto.

2. In a display device for apparatus comprising a plurality of major elements and a number of minor elements appurtenant to each major element and adapted for use therewith, the combination of a standard, 100 105 110

means supporting the major elements thereon, and a string of minor elements hung from each major element.

3. In an advertising and display device for outlet boxes, a support, an outlet box body fixed thereon, and a string of covers hung from the box body in such manner that any one of them may be fitted to the box body.
- 10 4. In an advertising and display device for a line of outlet boxes comprising a plu-

rality of box bodies and a number of covers appurtenant to each box body, the combination of a standard, means supporting the box bodies on the standard, and means forming strings of covers, each string being hung adjacent the box body which the covers on it fit.

In witness whereof, I have hereunto set my hand this 7th day of March, 1922.

GEO. T. FIELDING.
